Primary Examiner — Robert M Spear*Assistant Examiner* — Marissa J Cash(74) *Attorney, Agent, or Firm* — Fish & Richardson P.C.(57) **CLAIM**

The ornamental design for a drill head for dental implant surgery, substantially as shown and described.

DESCRIPTION

FIG. 1 is a front perspective view of a drill head for dental implant surgery.

FIG. 2 is a right side view of my design.

FIG. 3 is a left side view of my design.

FIG. 4 is a front end view of my design.

FIG. 5 is a rear end view of my design.

FIG. 6 is a top view of my design; and,

FIG. 7 is a bottom view of my design.

The broken lines illustrate environmental features that form no part of the claimed design.
